UNITED STATES PATENT OFFICE.

HARRY H. BAER, OF CLEVELAND, OHIO.

CARBURETER.

1,277,173.

Specification of Letters Patent. Patented Aug. 27, 1918.

Application filed October 27, 1917. Serial No. 198,778.

To all whom it may concern:

Be it known that I, HARRY H. BAER, a citizen of the United States, residing at Cleveland, in the county of Cuyahoga and State of Ohio, have invented a new and useful Carbureter, of which the following is a specification.

This invention relates to improvements in carbureters for internal combustion engines of automobiles or motor-driven conveyances, and pertains more especially to a bi-fuel carbureter which is adapted for the utilization of both gasoline and kerosene or any two volatile hydrocarbons varying in density or specific gravity or otherwise, and comprises means whereby the operator is enabled to start the engine by the use of one of said fuels and then to feed the other of said fuels, and involves the use of two fuel-chambers and means for controlling the feeding of fuel from each of said chambers to the mixing or carbureting chamber of the carbureter.

One object of this invention is to provide improved means for selectively feeding, into the carbureting chamber, two suitable fuels, such, for instance, as gasoline and kerosene, and requiring the one more air than the other to produce the proper combustible and explosive mixture, so that the engine may be started upon one fuel, such, for instance, as gasoline and then operated by feeding the other fuel, such, for instance, as kerosene, to said chamber.

Another object is to facilitate and expedite the commingling of the fuel and air supplied to the carbureting chamber and to more rapidly and thoroughly vaporize the fuel within said chamber.

Another object is to provide means whereby a supply of air to an air-and-fuel mixture in the carbureting chamber is automatically varied as required in shifting or changing from the one to the other fuel during the operation of an internal combustion engine.

Another object is to facilitate the assembly of the component parts of a carbureter of the character indicated and to render the carbureter simple and durable in construction, reliable in its operation, and not liable to get out of order.

With these objects in view, and to attain any other object hereinafter appearing, this invention consists in certain features of construction, and combinations and relative ar-

rangement of the parts, hereinafter described in this specification, pointed out in the claims and illustrated in the accompanying drawings.

In said drawings, Figure 1 is a central vertical section of a carbureter embodying my invention. Fig. 2 is a horizontal section taken along the line 2—2, Fig. 1. Fig. 3 is a horizontal section taken along the line 3—3, Fig. 1. Fig. 4 is a vertical section taken along the line 4—4, Fig. 1. Fig. 5 is a vertical section of a portion of the carbureter and corresponds with the corresponding portion illustrated in Fig. 1, except as to the position of the fuel-feed-controlling valve and movable parts operatively connected with said valve.

In said drawings, A indicates the body of a carbureter embodying my invention, which body is preferably composed of a single metal casting. Within said body are formed an air-chamber 10 and two fuel-chambers 11 and 12. The air-chamber 10 is arranged intermediately of the lower portions of the fuel-chambers 11 and 12 and extends below said fuel-chambers. Said fuel-chambers are therefore arranged at opposite sides respectively and externally of the air-chamber 10. I have chosen to describe my improved carbureter in connection with the use of gasoline and kerosene as the fuels to be fed from the fuel-chambers 11 and 12 to the mixing or carbureting chamber hereinafter referred to, and it will be understood that the chamber 11 is supplied with gasoline, and the chamber 12 with kerosene, and that 13 indicates the level of the fuel-body as desired to be maintained in said chambers.

Each fuel-chamber is provided at the bottom with a fuel-intake 14, and B indicates a pipe for conducting fuel to said intake from a fuel-supply source (not shown). The fuel-intake 14 of each fuel-chamber is shown closed by a suitably applied valve C which is operatively connected in any approved manner with one end of a lever D arranged internally of the upper end of said chamber and shown horizontally pivoted or fulcrumed, as at 15, centrally between the ends 105 of the lever, to an externally screw-threaded head E which is screwed into the body A of the carbureter and forms a removable top or cover for said chamber, and a float G is suspended from the opposite end of said lever and arranged within said chamber. It will be observed therefore that the

fuel in the fuel-chambers is maintained at a predetermined level, and obviously when the fuel in a fuel-chamber falls below said level the float G in said chamber descends and thereby opens the connected valve C and permits fuel to flow into said chamber at the intake 14 of the chamber until the desired level of fuel has again been restored in the chamber by the ascent of the float into its valve-closing position shown in Fig. 1.

Each fuel-chamber is in communication near its lower extremity with a horizontally arranged duct 16 formed in the body A of the carbureter, and the ducts 16 leading from the two fuel-chambers are preferably substantially in line endwise, as shown in Figs. 1 and 5, and connect with a substantially horizontal valve-containing bore 17 formed centrally and arranged transversely of the body-portion 18 of a fuel-feeding nozzle arranged internally of the air-chamber 10. The body-portion 18 of the nozzle extends therefore transversely of the air-chamber 10 and is preferably integral with the body A of the carbureter, and H indicates a rotatable horizontally arranged plug-valve occupying the bore 17 and consequently arranged transversely of and seated in said body-portion of the nozzle. Said nozzle has an upwardly projecting member 19 arranged centrally of the air-chamber 10 and having two spaced passages 20 and 21 connecting with the bore 17 in the body-portion of the nozzle and extending from said bore to the upper end of said upwardly projecting member of the nozzle and discharging upwardly into the mixing or carbureting chamber 22 of the carbureter. The valve H is a bi-way valve, having two angular ports 23 and 24, and the relative arrangement of said ports, the passages 20 and 21 in the upwardly projecting member of the nozzle and the ducts 16 leading from the fuel-chambers 11 and 12 is such that upon the rotation of said valve the required extent in one direction the port 23 in the valve establishes communication between the passage 20 in the nozzle and the fuel-conducting duct 16 leading from the chamber 11, as shown in Fig. 1, and that upon the rotation of the valve the required extent in the opposite direction the port 24 in the valve establishes communication between the passage 21 in the nozzle and the fuel-conducting duct 16 leading from the chamber 12, as shown in Fig. 5. I would here remark that the body A of the carbureter extends farther downwardly at one side of the air-chamber 10 than at the opposite side of said chamber 60 so as to form a lateral abutment for a dish-shaped member I arranged to form the bottom of said chamber, and that said member I is provided with the air-intake 26 for said chamber, and said intake communicates with a pipe 27 for supplying warm air at said in-

take to said chamber. The member I is attached, preferably removably by a screw 28 arranged centrally of said member and threaded into the body 18 of the fuel-feeding nozzle, as shown in Figs. 1, 4 and 5. By 70 the construction hereinbefore described it will be observed that my improved carbureter comprises two ducts 16 for conducting fuel to be fed to the carbureting chamber 22 from different fuel-supply sources, that a 75 fuel-feeding nozzle is arranged to discharge into said chamber and comprises a valve or fuel-feed-controlling means arranged and adapted to be operated to establish communication through said nozzle between said 80 chamber and the one or the other of said ducts, and that the air-chamber 10 and its air-intake 26 and the pipe 27 constitute means for supplying air to the carbureting chamber adjacent and around the discharging end of said nozzle.

The plug-valve H (see Figs. 3 and 4) extends through the body-portion 18 of the nozzle and is provided centrally of its diametrically smaller end with an axial stem 90 30 which extends externally of the body A of the carbureter. The valve-stem 30 is provided at its outer end with an upwardly projecting arm 31 which is spaced from the body A of the carbureter and extends between two spaced arms or members 32 rigid with and projecting laterally and outwardly from said body A and arranged to cooperate with said arm of said valve-stem in limiting rotation of said valve in opposite directions respectively. The relative arrangement of the parts is such that the valve H is in the position shown in Fig. 1 and establishes communication between the carbureting chamber and the duct 16 leading from 105 the gasoline-chamber 11, or is in the position shown in Fig. 5 and establishes communication between the carbureting chamber and the duct 16 leading from the kerosene-chamber 12, according as the arm 31 110 of the valve-stem 30 has been actuated against the one or the other of the stop-forming members 32. Upon installing my improved carbureter in an automobile said arm 31 is of course operatively connected in 115 any approved manner with a lever (not shown) within reach of the operator. I would also remark that preferably a helical spring 33 is mounted on the valve-stem 30 between the arm 31 of said stem and the 120 body A of the carbureter and acts to retain the valve H in proper engagement with its seat in the body-portion 18 of the nozzle. It will also be observed that said valve is provided at its diametrically larger end with 125 a laterally projecting arm 34 for the purpose hereinafter appearing.

The mixing or carbureting chamber 22 is formed above or forward of the discharging end of the fuel-feeding nozzle and internally 130

of a substantially vertically arranged tubular member K, and the upper part of said member K is larger diametrically than the lower part of said member, and said member 6 K is seated, as at 36, at the lower end of its upper and diametrically larger part on the body A of the carburetor. The lower and diametrically smaller part of said member K depends into said body A and has the 10 portion thereof which extends upwardly from adjacent the discharging end of the fuel-feeding nozzle considerably smaller diametrically than the upper part of said member K and not much larger in diameter than 15 but arranged concentrically relative to said end of said nozzle. The carbureting chamber 22 is therefore considerably smaller transversely adjacent and next above or forward of said end of said nozzle than above 20 the body A of the carburetor, and I would here remark that the lower end-portion 37 of the lower part of the member K extends and flares downwardly around the upper portion of the upwardly projecting member 25 19 of said nozzle and forms the upper end-portion of the surrounding wall of the air-chamber 10. The member K (see Fig. 4) is secured to the body A preferably removably by a screw 38, and composed preferably 30 of a single metal casting.

A heating chamber 40 is formed in the body A around and next externally of the lower part of the member K and consequently around the lower portion and externally of the carbureting chamber and around the upper portion and externally of the air-chamber 10 and is in communication, as at 41, with a heating chamber 42 formed in said body A and externally of the kerosene-chamber 12. A pipe 43, such, for instance, as the exhaust-pipe leading from the engine, is arranged to supply a heating agent to the chamber 42, and an outlet-pipe 44 leads from the chamber 40. The heating of the lower part of the member K facilitates the vaporizing of the fuel fed into the carbureting chamber by the fuel-feeding nozzle.

Within the upper end of the upper and diametrically larger portion of the carbureting chamber 22 is arranged the usual throttle-valve L for controlling the passage upwardly from or out of said chamber of the combustible and explosive air-and-fuel mixture formed in said chamber. The valve 55 L is shown open and connected to and carried by a shaft 46 extending transversely and externally of and supported from, the member K and provided externally of the carbureting chamber 22 with an arm 47, and 60 upon installing my improved carburetor in an automobile said arm 47 is of course operatively connected in any approved manner with a lever (not shown) within reach of the operator.

65 M indicates adjustable needle-valves ar-

ranged to regulate the discharge of fuel from the passages 20 and 21 in the fuel-feeding nozzle and extending through corresponding holes 48 formed in the lower part of the member K and threaded into and extending externally of the body A of the carburetor, as shown in Fig. 4.

The carbureting-chamber-forming member K is provided at one side and above the body A with a lateral aperture 50, and an externally screw-threaded tubular member 51 is screwed at said aperture into said member K. The tubular member 51 has a portion 52 thereof forming a bearing and external support for a sleeve P which is arranged substantially horizontally and transversely of the carbureting chamber 22 and slidably mounted on and shiftable endwise of a correspondingly arranged rod 53 which extends through and beyond the ends of said sleeve. 75 The rod 53 preferably extends transversely of and through the carbureting chamber 22 and is supported from the member K. A valve-casing 54 which extends circumferentially of and is arranged concentrically relative to the rod 53 and sleeve P is threaded at its inner end on to the tubular member 51, and an air-conducting pipe 55 leading from any suitable warm-air-supply source is threaded into said valve-casing at the 80 outer end of said casing. Said pipe 55, the valve-casing 54 and the member 51 form a passageway for supplying air to the carbureting chamber, and the discharging end of said passageway forms a lateral air-inlet 100 of said chamber, and the supply of air by said passageway to said chamber is controlled by a valve R arranged in the outer end-portion of said valve-casing and slidably mounted on and shiftable endwise of 105 the rod 53. The valve R is normally in its closed position in which the valve is seated against an inwardly facing beveled seat 56 formed on and internally of the valve-casing 54, and hence said valve in opening moves 110 toward the carbureting chamber 22. The sleeve P is spaced from the valve R in the direction of the inner end of the valve-casing 54, and a helical spring 57 is coiled around the rod 53 and confined between said valve and a shoulder 58 formed on the adjacent end of the sleeve. The spring 57 is normally under tension and acts to retain the valve R in its closed and normal position. The spring 57 is arranged therefore 115 internally of the valve-casing 54, and the sleeve P extends from the spring through the tubular member 51 and into the carbureting chamber a suitable distance and abuts internally of said chamber against two arms 120 61 formed on and projecting upwardly from a collar 60 with which the upper end of an upright rod T arranged internally of the air-chamber 10 and carbureting chamber is 125 provided. The rod T extends from the col- 130

lar 60 downwardly to and is operatively connected at its lower end with the arm 34 of the plug-valve H. The collar 60 is preferably threaded onto the upper end of the rod T and therefore adjustable endwise of the rod as desired. The members 61 connected therefore to the rod T are arranged at opposite sides respectively of the horizontal rod 53 and interposed between the adjacent end of the sleeve P and an annular inwardly facing shoulder 62 formed on said horizontal rod and forming an abutment for the adjacent vertically arranged surface 63 of said members 61. The horizontal rod 15 53 is preferably threaded adjacent its shoulder 62 into the member K of the carbureter and therefore adjustable endwise as required to manually adjust the sleeve-engaging members 61 and the sleeve P endwise of said 20 rod for the purpose of regulating the tension of the spring 57 upon the assemblage of the parts. The sleeve-engaging surface 64 of each member 61 is inclined or sloping and faces upwardly, and the engaging end 25 face 65 of the sleeve P is inclined or sloping and faces downwardly. It will be observed therefore that each arm 61 of the collar 60 is wedge-shaped, and the relative arrangement of the parts is such that the 30 sleeve P is actuated toward the air-supply-controlling valve R by the wedge-shaped members 61, or farther away from said valve by the spring 57, according as said wedge-shaped members are elevated or lowered by 35 the ascent or descent respectively of the rod T. Obviously the spring 57 is placed under greater or less tension according as the sleeve P is actuated toward or from the valve R, and therefore the tension of said 40 spring is increased or reduced according as the rod T is shifted endwise in the one or the other direction. The relative arrangement of the parts is such that the rod T is in its lower position when the plug-valve 45 H or fuel-feed-controlling means is in the position shown in Figs. 1 and 3, establishing communication between the carbureting chamber 22 and the duct 16 leading from the gasolene-chamber 11, and that said rod is 50 elevated during the actuation of said valve or fuel-feed-controlling means from the position shown in Figs. 1 and 3 into the position shown in Fig. 5, and that when said valve or fuel-feed-controlling means is in 55 the position shown in Fig. 5 not only is communication established between the carbureting chamber and the duct 16 leading from the kerosene-chamber 12, but the spring 57 is under greater tension than in 60 the position of said valve or fuel-feed-controlling means shown in Figs. 1 and 3.

It will be observed that the air-supply-controlling valve R is arranged and adapted to be opened by the requisite suction created within the carbureting chamber 22 dur- 65

ing the operation of the engine, that the movement of said valve by any given suction within said chamber is reduced or increased according as the spring 57 is placed under greater or less tension, and that the 70 arm 34 of the plug-valve H, the rod T and its wedge-shaped members 61 and the sleeve P form such a connection between the spring or yieldable means 57 and the plug-valve or fuel-feed-controlling means that 75 the resistance offered by said spring or yieldable means to the opening of the air-supply-controlling valve R is increased or reduced according as communication is established by the plug-valve or fuel-feed-controlling means between the carbureting chamber and the one or the other of the ducts 16, and it will be observed also that 80 said connection between said plug-valve or fuel-feed-controlling means and the afore- 85 said spring or yieldable means is wholly independent of the throttle-valve L.

I would remark also that the air-supplying passageway extending through the valve-casing 54 has that portion of its surrounding wall which is formed by the central portion of said casing bulging outwardly, as at 66, Figs. 1 and 5, so as to result in a whirling motion of the air conducted by said passageway to the carbureting chamber and thereby facilitate the commingling of said air with the air-and-fuel mixture already formed and ascending within said chamber.

What I claim is—

1. In a carbureter, the combination, with a mixing or carbureting chamber, two ducts for conducting fuel to be fed to said chamber from different fuel-supply sources, a fuel-feeding nozzle arranged to discharge 105 into said chamber and comprising fuel-feed-controlling means arranged and adapted to be operated to establish communication through said nozzle between said chamber and the one or the other of said ducts, and 110 means for supplying air to said chamber adjacent said nozzle, said chamber being provided at a point spaced forwardly from said nozzle with an air-inlet, of a valve controlling the supply of air to said chamber at 115 said air-inlet and normally in its closed position and arranged and adapted to be opened by the requisite suction created within said chamber, and means whereby the movement of said valve by any given 120 suction is reduced or increased according as communication is established by the afore-said fuel-feed-controlling means between said chamber and the one or the other of the aforesaid ducts.

2. In a carbureter, the combination, with a mixing or carbureting chamber, two ducts for conducting fuel to be fed to said chamber from different fuel-supply sources, fuel-feed-controlling means employed in estab- 130

lishing communication between said chamber and the one or the other of said ducts, means for supplying air to said chamber adjacent said fuel-feed-controlling means, and 5 a throttle-valve arranged within said chamber and employed in controlling the passage from said chamber of the fuel-and-air mixture formed in said chamber, said chamber having an air-inlet intermediately of 10 said valve and the aforesaid air-supply means, of a valve controlling the supply of air to said chamber at said air-inlet and normally in its closed position and arranged and adapted to be opened by the 15 requisite suction created within said chamber, and means independent of the aforesaid throttle-valve and arranged and adapted to render the movement of the second-mentioned valve by a given suction 20 greater or less according as communication is established by the aforesaid fuel-feed-controlling means between said chamber and the one or the other of the aforesaid ducts.

3. In a carbureter, the combination, with 25 a mixing or carbureting chamber having an air-inlet, two ducts for conducting fuel to be fed to said chamber from different fuel-supply sources, fuel-feed-controlling means employed in establishing communication be- 30 tween said chamber and the one or the other of said ducts, a valve controlling the supply of air to said chamber at the aforesaid air-inlet and normally in its closed position and arranged and adapted to be opened by the 35 requisite suction created in said chamber, and yieldable means acting to retain said valve in its closed position, of means whereby the resistance offered by said yieldable means to the opening of said valve is 40 increased or reduced according as communication by the aforesaid fuel-feed-controlling means is established between the aforesaid chamber and the one or the other of the aforesaid ducts.

4. In a carbureter, a mixing or carbureting chamber having a lateral air-inlet, two ducts for conducting fuel to be fed to said chamber from different fuel-supply sources, fuel-feed-controlling means spaced down- 45 wardly from said air-let and employed in establishing communication between said chamber and the one or the other of said ducts, means for supplying air to said chamber adjacent said fuel-feed-controlling 50 means, a valve arranged to control the supply of air to said chamber at the aforesaid air-inlet and normally in its closed position and arranged and adapted to be opened by the requisite suction created in said chamber, yieldable means acting to retain said 55 valve in its closed position, and means arranged internally of the carbureter and capable of operation to increase or reduce the 60 resistance offered by said yieldable means 65 to the opening of said valve according as

the one or the other of the aforesaid ducts is selected by the aforesaid fuel-feed-controlling means as the passageway from which fuel is to be fed to the aforesaid chamber.

70

5. In a carbureter, the combination, with a mixing or carbureting chamber having an air-inlet, two ducts for conducting fuel to be fed to said chamber from different fuel-supply sources, fuel-feed-controlling means 75 arranged and adapted to be operated to establish communication between said chamber and the one or the other of said ducts, a valve controlling the supply of air to said chamber at the aforesaid air-inlet and normally in its closed position and arranged and adapted to be opened by suction created in said chamber, and a spring acting to retain said valve in its closed position, of means whereby said spring is placed under 80 greater or less tension according as the aforesaid fuel-feed-controlling means establishes communication between the aforesaid chamber and the one or the other of the aforesaid ducts.

85

6. In a carbureter, the combination, with a carbureting chamber, a suitably supported rod, a valve controlling a supply of air to said chamber and mounted on and movable endwise of said rod and normally in its 90 closed position and arranged and adapted to be opened by suction created in said chamber, two ducts for conducting fuel to be fed to said chamber from different fuel-supply sources, and fuel-feed-controlling means 95 capable of operation to establish communication between said chamber and the one or the other of said ducts, of a sleeve mounted on and shiftable endwise of the aforesaid rod and spaced from the aforesaid valve, a 100 spring under tension in either position of the sleeve and acting to retain said valve in its closed position, and means, controlled by the aforesaid operation of the fuel-feed-controlling means, for actuating the sleeve in 110 the direction required to increase the tension of the spring, said fuel-feed-controlling means establishing communication between the aforesaid chamber and the one or the other of the aforesaid ducts according as 115 said sleeve is in the one or the other of its positions.

105

7. In a carbureter, the combination, with a carbureting chamber, a suitable supported rod extending transversely of said chamber, 120 a valve controlling the supply of air to said chamber and slidably mounted on and movable endwise of said rod and normally in its closed position and arranged and adapted to be opened by suction created in said chamber, two ducts for conducting fuel to be fed to said chamber from different fuel-supply sources, and fuel-feed-controlling means capable of operation to establish 125 communication between said chamber and 130

135

140

145

150

155

160

- the one or the other of said ducts, of a sleeve mounted on and shiftable endwise of the aforesaid rod and spaced from the aforesaid valve, resilient means confined between said valve and the sleeve and under tension in either position of the sleeve and acting to retain said valve in its closed position, and mechanism controlled by the aforesaid operation of the fuel-feed-controlling means and arranged and adapted to actuate the sleeve in the direction required to place said resilient means under greater tension, or to permit said resilient means to actuate the sleeve in the opposite direction, 10 according as the operation of the fuel-feed-controlling means establishes communication between the aforesaid chamber and the one or the other of the aforesaid ducts.
8. In a carbureter, the combination, with 20 a carbureting chamber, two ducts for conducting fuel to be fed to said chamber from different fuel-supply sources, fuel-feed-controlling means capable of operation to establish communication between said chamber and the one or the other of said ducts, a valve controlling a supply of air to said chamber and normally in its closed position and arranged and adapted to be opened by suction created in said chamber, and a suitably supported rod extending into and loose relative to said valve and having a shoulder spaced from and facing toward the valve, of a sleeve mounted on and shiftable endwise of said rod between and spaced from said valve and said shoulder, a spring confined between the sleeve and said valve and acting to retain said valve in its closed position, a wedge-shaped member interposed between the sleeve and the aforesaid shoulder and arranged to actuate the sleeve toward the valve during movement of said wedge-shaped member endwise in one direction, and such a connection between said wedge-shaped member and the fuel-feed-controlling means that said wedge-shaped member is actuated endwise in the one or the other direction by the required operation of the fuel-feed-controlling means.
9. In a carbureter, the combination, with 50 a carbureting chamber, two ducts for conducting fuel to be fed to said chamber from different fuel-supply sources, fuel-feed-controlling means capable of operation to establish communication between said chamber and the one or the other of said ducts, a valve controlling a supply of air to said chamber and normally in its closed position and arranged and adapted to be opened by suction created in said chamber, of a suitably supported rod extending into and loose relative to said valve and having a shoulder spaced from and facing the valve, a sleeve mounted on and shiftable endwise of said rod between and spaced from said valve and said shoulder, a spring confined between the
- sleeve and said valve and acting to retain the valve in its closed position, a wedge-shaped member interposed between the sleeve and the aforesaid shoulder and arranged to actuate the sleeve toward the valve 70 during movement of said wedge-shaped member endwise in one direction, and such a connection between said wedge-shaped member and the fuel-feed-controlling means that said wedge-shaped member is actuated 75 endwise in the one or the other direction by the required operation of the fuel-feed-controlling means, the aforesaid rod being adjustable endwise.
10. In a carbureter, the combination, with 80 a carbureting chamber having a lateral air-inlet, two ducts for conducting fuel to be fed to said chamber from different fuel-supply sources, fuel-feed-controlling means capable of operation to establish communication between said chamber and the one or the other of said ducts, a suitably supported rod extending through said air-inlet and transversely of said chamber, and a valve controlling the supply of air to said chamber at 90 said air-inlet and mounted on and movable endwise of said rod and normally in its closed position, said rod having a shoulder spaced from the valve in the direction in which the valve moves in opening and facing toward the valve, of a sleeve mounted on and shiftable endwise of said rod between and spaced from said valve and said shoulder, a spring confined between said valve and the sleeve and acting to retain said valve 100 in its closed position, a wedge-shaped member interposed between the sleeve and the aforesaid shoulder, and an endwise shiftable rod operatively connected at one end to said wedge-shaped member and at its other end 105 to the fuel-feed-controlling means.
11. In a carbureter, the combination, with a carbureting chamber having a lateral air-inlet, two ducts for conducting fuel to be fed to said chamber from different fuel-supply sources, fuel-feed-controlling means capable of operation to establish communication between said chamber and the one or the other of said ducts, a suitably supported rod extending through said air-inlet and transversely of said chamber and provided internally of said chamber with a shoulder facing in the direction of said air-inlet, and a valve controlling the supply of air to said chamber at said air-inlet and mounted on 115 and movable endwise of said rod and normally closed and arranged and adapted to be opened by suction created in said chamber, of a sleeve mounted on and shiftable endwise of said rod between said valve and the aforesaid shoulder, resilient means confined between said valve and the sleeve and acting to retain said valve in its closed position, an endwise shiftable rod operatively connected at one end to the fuel-feed-con- 120
- 125
- 130

trolling means, and a collar threaded onto the other end of the last-mentioned rod and having two wedge-shaped members arranged at opposite sides respectively of the first-mentioned rod and interposed between the sleeve and the aforesaid shoulder.

12. In a carbureter, an upright tubular member which has its lower part diametrically smaller than its upper part and terminating in a downwardly flaring portion forming the surrounding wall of the upper end-portion of an air-chamber and forms a carbureting chamber having a lateral air-inlet arranged above said air-chamber, a valve controlling the supply of air to said carbureting chamber at said air-inlet and normally closed and arranged and adapted to be opened by suction created in the carbureting chamber, a spring acting to retain said valve in its closed position, a body which surrounds the lower part of the aforesaid tubular member and participates in the formation of the aforesaid air-chamber and is provided with two fuel-chambers arranged

externally of and extending above said air-chamber, two ducts forming outlets the one for one of the fuel-chambers and the other for the other fuel-chamber, fuel-feed-controlling means capable of operation to establish communication between the carbureting chamber and the one or the other of said ducts, means for supplying air to the aforesaid air-chamber from below the fuel-feed-controlling means, and means whereby the tension of the aforesaid spring is increased or reduced according as the aforesaid operation of the fuel-feed-controlling means establishes communication between the carbureting chamber and the one or the other of the aforesaid ducts.

In testimony whereof I sign the foregoing specification in the presence of two witnesses.

HARRY H. BAER.
